FOOD MIXING APPARATUS

Fred E. Kaempf, Wausau, Wis.

Application August 6, 1956, Serial No. 42,512

Term of patent 14 years

(Cl. D44—1)

Fig. 1

Fig. 2

Fig. 3

Figure 1 is a view in perspective of a food mixing apparatus, showing my new design,

Figure 2 is an end elevational view on a smaller scale, and

Figure 3 is a similarly scaled side elevational view.

I claim:

The ornamental design for a food mixing apparatus, substantially as shown.
